GAME BOARD

John Sneal, Vancouver, British Columbia,
Canada

Application July 19, 1948, Serial No. 147,671

Term of patent 14 years

(Cl. D34—5)

To all whom it may concern:

Be it known that I, John Sneal, a citizen of the Dominion of Canada, residing at Vancouver, in the province of British Columbia, Canada, whose street address is 717 Robson Street, has invented a new, original, and ornamental Design for a Game Board, of which the following is a specification, reference being had to the accompanying drawing, forming part thereof.

Fig. 1 is a plan view of a game board, showing my new design; and

Fig. 2 is an end elevational view thereof.

The dominant features of my design reside in that portion shown in full lines in the drawing.

I claim:

The ornamental design for a game board, as shown and described.

JOHN SNEAL.
